UNITED STATES PATENT OFFICE.

JOHN W. CULP, OF ELKHART, INDIANA, ASSIGNOR TO MODERN BURGLAR & FIRE ALARM COMPANY, OF ELKHART, INDIANA.

BURGLAR OR FIRE ALARM SYSTEM.

SPECIFICATION forming part of Letters Patent No. 783,996, dated February 28, 1905.

Application filed June 25, 1904. Serial No. 214,197.

To all whom it may concern:

Be it known that I, JOHN W. CULP, a citizen of the United States, and a resident of Elkhart, in the county of Elkhart and State of Indiana, have made a certain new and useful Invention in Burglar or Fire Alarm Systems; and I declare the following to be a full, clear, and exact description of the same, such as will enable others skilled in the art to which it applies to make and use the invention, reference being had to the accompanying drawing, and to letters or figures of reference marked thereon, which form a part of this specification.

The figure is a vertical longitudinal sectional view illustrating the invention.

The invention relates to means for giving notice in case of fire or burglary in buildings; and it consists in the novel construction and combinations of parts, as hereinafter set forth.

In the accompanying drawing, illustrating the invention, the letter *a* designates an outer metallic case which is designed to be attached to the outer wall of the building to be protected. This case is provided with a tubular extension *d*, which projects from the rear of the case into the building. It is also provided with a drop-door *b*, whereby access can be had to the interior, such door having a suitable lock, as at *c*. To the door is connected near its hinged portion an inside flat spring device *a'*, which is designed when the door is opened to come in contact with the inside case *e* and deenergize the magnet *M*, thereby setting off the alarm in the inner case. This provision is made to guard against tampering with the lock. The door is designed to be provided with a strong wire-netting at *b'*.

Within the outer case is located the inner case *e*, which is of similar form to the outer case, but a little smaller, so that it will have an interval around it between its wall and that of the outer case. Insulating-strips *f* are placed between the inner and outer cases. The inner case is also provided with a tubular extension *z*, projecting in rear within the tubular extension of the outer case and insulated therefrom. The inner case is designed

to contain the alarm and signal devices and when placed within the outer case is entirely insulated therefrom and from its tubular extension, except in so far as the conducting wires hereinafter described are concerned. The alarm-bell is indicated at *n* and its electromagnet at *p* within the inner case, which also contains the red light *q* of incandescent character, the wires *P* of which extend through the tubular extension to the source of electric-light current. The wires 6 and 8 of the alarm-circuit also extend through the tubular projections of the cases into the buildings.

The inside of the building is wired in connection with the windows and doors, as at 5, and there is also provided along the walls of the building a system of fusible wiring, as at 10. This wiring is designed to melt apart at a low degree of heat to cut out the electromagnet *N*.

M denotes an electromagnet which is normally in circuit, thus holding its armature-switch *V* out of engagement with contact-point *W*.

N is an electromagnet normally energized by battery *J* and holding armature-switch *I* out of touch with contact-point *U*.

The electric-light wiring *P* is provided with a break near the magnet *N* and a pivoted switch *Q*, which is held out of contact with the other terminal of said break by the armature-switch *I* when in circuit, said switch having an insulated arm *R*, serving as a rest or catch. In this manner it is designed to cut out the electric-light current by the energization of the magnet *N*, which is normally in circuit. The switch-armature *V* of magnet *M* is connected by wire 7 to battery *K*.

W denotes a contact in connection with the alarm-wire 6, and when the armature-switch *V* falls through any short-circuiting or breaking of the normally closed circuit in the magnet *M* the current will pass through the wires 6, 7, and 8 and battery *K*, sounding the alarm.

The wire 2 leads from one side of battery *J*, forming circuit with the inside tubing and case and extending by wire 3 to one side of

2
magnet M. The other wire, 4, from battery J forms circuit with the outside tubing and case, which is connected with wire 5, which extends to suitable connections upon doors 5 and windows and continues to the other side of magnet M. The fusible metal wiring 10 extends from battery J through such parts of the building as are liable to outbreaks of fire and is fully connected with one side of mag- 10 net N. The other wire, 11, from battery J is also in connection with magnet N, which is normally in closed circuit. Wires 12 and 14 are connected with wiring 5 and provided with switch 13, which may be closed when it is de- 15 sired to cut out the wiring system to the doors and windows without deenergizing magnet M. The contact part U is connected to the wire 4 of battery J by wire 16, and the armature-switch I is connected by wire 17 to the wire 2 of the same battery. 20

When the door or window connection is broken, magnet M will be deenergized and its switch-armature will fall, engaging contact W and putting the alarm-circuit in action for 25 battery K. Should the fusible wiring melt at any point, the magnet N will become de-energized and its switch-armature I will drop and close circuit in contact U, deenergizing magnet M and allowing the switch-armature 30 V to drop and closing the bell-circuit. At the same time the switch Q will be released and will close the electric-light circuit. In the case of burglary when the circuit of the wiring of the windows and doors is broken 35 the bell-alarm will ring; but when fire occurs, short-circuiting the fusible-wire system, both the alarm-circuit and the light-circuit will be put in action.

Having described the invention, what I

claim, and desire to secure by Letters Patent, 40
is—

1. The electric alarm, consisting of the outer case, and its tubular extension, forming a part of a protection-circuit normally closed on an electromagnet, and including an 45 inner case, and its inner tubular extension, insulated from said outer case and its tubular extension, and containing an alarm device having an electromagnet in a normally open circuit, the armature of the electric magnet 50 in the normally closed circuit moving to close the normally open circuit upon the deenergization of its magnet, substantially as specified.

2. The electric alarm, consisting of the 55 outer case, forming a part of a burglar-protection circuit normally closed on an electromagnet, and including an inner case, insulated from said outer case, and containing an alarm device, having an electromagnet in a normally 60 open circuit, the armature of the electric magnet in the normally closed circuit moving to close the normally open circuit upon the deenergization of its magnet, an electric light in a normally open circuit having a switch in in- 65 sulated engagement with a second switch-armature, a second normally closed circuit, an electromagnet energized thereby to normally hold said second switch-armature open and a fusible wire in said second closed circuit, sub- 70 stantially as specified.

In testimony whereof I affix my signature in presence of two witnesses.

JOHN W. CULP.
